UNITED STATES PATENT OFFICE.

GEORGE TAUBALD, OF CINCINNATI, OHIO.

WATER-HEATER.

SPECIFICATION forming part of Letters Patent No. 593,621, dated November 16, 1897.

Application filed July 12, 1897. Serial No. 644,339. (No model.)

To all whom it may concern:

Be it known that I, GEORGE TAUBALD, a citizen of the United States, residing at Cincinnati, in the county of Hamilton and State 5 of Ohio, have invented certain new and useful Improvements in Water-Heaters; and I do hereby declare the following to be a full, clear, and exact description of the invention, reference being had to the annexed drawings, 10 which form a part of this specification.

This invention relates to those water-heaters which comprise an inclosing shell or casing, a lower receiving-chamber, an upper discharging-chamber, a series or stack of 15 vertical pipes connecting said chambers, and a gas or vapor burner at the base of the apparatus; and my improvement consists in fitting an extra burner longitudinally of and within the heater. This extra burner has 20 ventages adapted to discharge jets of ignited gas against the sides of the pipes connecting the aforesaid pair of chambers. Furthermore, the base-burner and longitudinal burner can be used jointly when occasion requires, or 25 either one of them can be employed independently of the other, as hereinafter more fully described.

In the annexed drawings, Figure 1 is a vertical section of my improved water-heater. 30 Figs. 2 and 3 are horizontal sections of the apparatus, taken, respectively, at the lines Y Y and Z Z of Fig. 1.

A B represent two ring-shaped or annular castings which are about five or six inches 35 in diameter and thick enough to stand any pressure ordinarily used with city water-works, as the inlet of the apparatus is preferably in direct communication with a street-main, the same as heaters applied to stoves, 40 ranges, &c. This inlet C usually passes horizontally into the lower ring B, and the latter is provided on its upper side with a number of interiorly-threaded nipples b, wherewith are engaged vertical tubes D. These tubes 45 are from twelve to twenty inches long and about three-quarters of an inch in diameter, their upper ends being engaged with screw-threaded nipples a, projecting from the under side of the ring A, which latter has the 50 outlet-pipe E attached to it. These rings and their connecting-pipes are housed within

a cylindrical shell or casing F, which is double, as at F', by which means an annular chamber is afforded for a non-conducting packing G, of asbestos or mineral wool or 55 other suitable material or materials. This inclosing shell may be set upon legs or feet f, or it may be attached to a wall or other firm support and has secured to its base by a number of lugs h a ring-shaped burner H, 60 having one or more series of ventages h' for the escape of gas or other combustible vapor or fluid.

I is an inlet-pipe that supplies the burner H with gas. Passing up through the center 65 of this ring H and occupying an axial position within the heater is a vertical pipe J, having a series of ventages j for the escape of gas or other burning vapor or fluid.

Shell F F' has an annular cap K secured to 70 it, and this cap has fitted upon it a readily-detachable cover L, whose neck l is adapted to have a smoke-pipe applied thereto.

After this apparatus has been set up in the desired location the pipe C is connected 75 with some source of water-supply, while the other pipe E leads to any suitable outlet, said pipes being provided with suitable cocks capable of being opened and closed at pleasure. Ordinarily the inlet-pipe C is in communication with a street-main, but said pipe may lead directly into the bottom of a bathtub when the heater is located in a bathroom. Again, the pipe E may communicate 80 with the upper part of said tub, or it may connect with a hot-water pipe of an ordinary heater, so as to be used in conjunction with the latter or independently of it, or the apparatus may be mounted directly upon or 85 near a kitchen-sink, so as to afford a constant 90 supply of hot water for culinary purposes.

Other arrangements of the apparatus will readily suggest themselves to plumbers and those engaged in putting up heating appliances generally.

As the apparatus is constantly filled with 95 water, no precaution is necessary in using it, after lighting the gas burner or burners. If there is no especial hurry for hot water, the single burner H may be used, and as the gas 100 jets issue from its ventages h' the heat ascends within the apparatus and escapes at the col-

lar *l* at a very low temperature on account of it being absorbed by the rings *A* *B* and stack of pipes *D*, of which latter eight are preferred. Again, very little heat is radiated from the apparatus, because it is so completely surrounded by the non-conducting filling *G*. Consequently the gas is almost wholly utilized within the apparatus, the result being the establishing of a rapid circulation up the pipes *D* and a speedy heating of the water with a minimum consumption of gas; but if it is desired to use the apparatus as an instantaneous water-heater the central burner *J* is brought into use in conjunction with the base-burner *H*, and in a few minutes thereafter scalding water will be discharged in a constant stream from the cock or outlet attached to pipe *E*. This rapid production of scalding water is due to the fact that the burning jets issuing from the numerous ventages *j* strike the sides of pipes *D* at right angles thereto, and as this central burner *J* extends up almost to the ring *A* it is evident a most intense heat is soon concentrated within the apparatus; but as soon as the demand for scalding water has ceased said burner is shut off and the lower one *H* used alone.

Finally, the outer casing or shell can be nickel-plated or made of polished brass, so as to present a very attractive appearance; but

for a cheaper grade of heaters said shell may be composed of Russia iron.

I claim as my invention—

1. A water-heater comprising an inclosing casing; a lower receiving-chamber, provided with an inlet; an upper discharging-chamber, provided with an outlet; a series of pipes connecting said chambers; a base-burner below said receiving-chamber; and an extra burner arranged longitudinally of and within the heater, and having ventages that discharge against the sides of said connecting-pipes, for the purpose described. 35 40

2. A water-heater comprising an inclosing casing; a lower ring *B* fitted therein, and provided with an inlet; an upper ring *A*, provided with an outlet; a series of pipes *D*, connecting said rings; an annular burner *H*, at the base of the heater, and provided with openings *h'*; and a longitudinal burner-pipe *J*, provided with openings *j*, discharging against said pipes *D*, all as herein described, and for the purpose stated. 45 50

In testimony whereof I affix my signature in presence of two witnesses.

GEORGE TAUBALD.
